Primary Examiner—Brian N. Vinson*Attorney, Agent, or Firm*—Rhodes, Coats & Bennett, L.L.P.**[57] CLAIM**

The ornamental design for a TV canopy, as shown and described.

DESCRIPTION

FIG. 1 is a bottom front right perspective view of a TV canopy showing my new design;

FIG. 2 is a front elevational view thereof;

FIG. 3 is a rear elevational view thereof;

FIG. 4 is a right side elevational view thereof, the left side being a mirror image of that shown; and,

FIG. 5 is an enlarged bottom front left perspective view thereof.

The broken lines indicating a bed and portions thereof, and a television, in the views are for illustrating environmental elements only and form no part of the claimed design.
